UNITED STATES PATENT OFFICE.

JAMES H. ALEXANDER, OF PHILADELPHIA, PENNSYLVANIA, ASSIGNOR TO
THOMAS DEVLIN & CO., OF SAME PLACE.

DESIGN FOR A STOVE-PLATE LIFTER.

SPECIFICATION forming part of Design No. 16,598, dated April 6, 1886.

Application filed February 18, 1886. Serial No. 192,460. Term of patent 7 years.

To all whom it may concern:

Be it known that I, JAMES H. ALEXANDER, a citizen of the United States, residing at Philadelphia, in the county of Philadelphia and State of Pennsylvania, have invented 5 a certain new and useful Design for a Stove-Plate Lifter; and I do hereby declare the following to be a full, clear, and exact description of the invention, reference being had to 10 the accompanying drawing, which form part of this specification, in which the figure is a plan view of my design.

My design consists in the peculiar ornamentation of the shank of the lifter, such 15 shank comprising all of that part beyond the ears *a a* of the hook *B*. One-half or about one-half of the shank, being the grasping part *B'*, is open or lattice work, while the other half or part, *C*, is solid. The ornamentation of the lattice work consists, essentially, 20 of four semicircles or segments, *d d'* and *e e'*, grouped in pairs, as shown, their ends touch-

ing two confining sides, *f f'*, with an intermediate figure consisting of two parallel bars, *f' f'*, connected by a diagonal bar, *f''*, forming 25 the letter **N**. The ornamentation of the part *C* consists of a stippled surface, *g*, between edge lines *h h'*, and having a vine, *i*, in relief thereon.

What I claim is—

The design for a stove-plate lifter herein shown, consisting of the open-work part *B'*, comprising four segments grouped in pairs between confining sides and inclosing a letter **N**, and the solid part *C*, having a stippled surface between side lines and a vine in relief thereon, substantially as set forth. 30

In testimony that I claim the foregoing I have hereunto set my hand this 16th day of January, 1886.

JAMES H. ALEXANDER.
